BABY SWING

Joseph C. Anderegg, Algoma, Wis., assignor to
 Algoma Net Company, Algoma, Wis., a corpora-
 tion of Wisconsin

Application April 19, 1941, Serial No. 389,429

7 Claims. (Cl. 155—17)

This invention relates generally to the class of chairs and seats and pertains particularly to improvements in baby swings.

In the usual baby swing which is designed to be suspended from either a door frame or a portable supporting frame, a number of suspension straps, usually four, are made use of. Two of these straps are customarily attached to the back of the seat or swing and two are attached to the frame of the seat proper adjacent the front thereof and all four straps extend upwardly to a pair or to a single suspension element. In order to maintain these straps spaced apart so that undesirable strain will not be placed upon the body of the swing, there is employed a rectangular spacer which is interposed between the straps to keep them parallel throughout the major portion of the length thereof. Such spacers interfere with the proper use of the swing since it is difficult to lift a child into or out of the swing without striking his head against the spacer. Such swings also have the backs thereof perfectly vertical with the back straps extending straight up therefrom to the spacer device. This is an inconvenient feature since it requires the child to sit perfectly upright at all times instead of permitting him to lean back in a more comfortable position.

The principal object of the present invention is to provide an improved baby swing wherein the frame for the swing is designed in a novel manner to provide a back portion which will be constantly maintained at a slightly rearwardly inclined position with respect to the horizontal portion of the frame which suspends the material for the bottom or seat of the swing and in which the suspension straps can converge at their upper ends for connection with suspension elements without collapsing the frame of the swing and without necessitating the employment of rectangular spacers.

Another object of the invention is to provide in a baby swing an improved frame construction for maintaining the seat portion of the swing and the back portion in a prescribed relation, wherein the portion of the frame to which the back of the swing is connected will be held at an upwardly and rearwardly extending angle with respect to the other portion to which the seat is attached, when the swing is suspended, but such back frame portion, while being held against folding forwardly over the seat, can be folded rearwardly and across the under side of the seat and seat frame when the swing is taken down, thus permitting the ready folding and storage of the swing or its easy transportation.

The invention will be best understood from a consideration of the following detailed description taken in connection with the accompanying drawings, it being understood, however, that the

invention is not to be considered as limited by the specific illustration or description but that such illustration and description constitutes a preferred embodiment of the invention.

5 In the drawings:

Fig. 1 is a view in side elevation of an embodiment of a swing constructed in accordance with the present invention.

Fig. 2 is a view in front elevation of the same.

10 Fig. 3 is an enlarged fragmentary view in side elevation of one joint between a side of the frame back and the adjacent bar of the seat portion of the frame.

Fig. 4 is a view in rear elevation of the joint 15 shown in Fig. 3.

Fig. 5 is a view in perspective of the joint per se.

Fig. 6 is a view in front elevation of a modified embodiment of the invention.

20 Fig. 7 is a detailed perspective view of the connection between an end of a single spreader bar and the upper end portions of a pair of suspension straps.

Fig. 8 is a view in perspective of an end of the 25 single suspension bar without the straps connected therewith.

Referring now more particularly to the drawings, there is shown in Figs. 1 and 2, a portable frame for the support of the swing structure, this frame being indicated generally by the numeral 1 and comprising the two substantially U-shaped structures having the side legs 2 and the cross-connecting bars 3, the latter bars being hingedly joined together by a hinge coupling 4 whereby the two inverted U-structures may be folded together into parallel relation. When spread apart, the two structures of the supporting frame are maintained in braced relation by hinged coupling links 5. The elements 4 of the frame are here shown as having depending eye portions 6 with which are connected suspension chains 7 which at their lower ends are coupled to spring units 8 to which the baby swing is attached. In the form of the invention shown in Fig. 1, two of these spring units are disposed in spaced relation in the frame since the swing supporting straps are arranged in two pairs, each pair extending upwardly from a side of the swing to be coupled with a unit 8.

50 In the double suspension shown in Figs. 1 and 2, there are provided at each side of the swing, which is indicated as a whole by the numeral 9, the pair of straps 10 and 11. Each of the straps 10 is at the front of the swing and each of the 55 straps 11 is at the rear thereof and these straps converge upwardly and are joined by loops 12, each with a suspension spring unit 8. In Fig. 6, a single suspension is illustrated and indicated by the numeral 13, and in this form of suspension means, the two pairs of straps, each at one

side of the swing structure 9, extend upwardly through an end of a single horizontal spacer bar 14 from which they are drawn together toward the vertical center of the spring structure where the four straps are joined in a single loop 15 for attachment to the single suspension element 13. This element may be attached to a single spring unit such as the unit 8 of Figs. 1 and 2, and in both of these constructions the spring units may either be suspended from a portable frame as shown, or from any other suitable support such as the head of a door frame or the like.

The front and rear straps of the two pairs shown in Fig. 6 are indicated respectively by the numerals 10^a and 11^a, and in this arrangement it is preferred that the single spacing bar which extends transversely of the swing well above the same and in the plane of the vertical transverse center, have each end formed into a square loop 16 with a reverted or inturned center bar 17 which is in spaced parallel relation with the outer bars 18. The straps 10^a and 11^a of each pair are threaded through a square loop 16 passing across one side of the center bar 17 and across the remote sides of the two other bars 18, as shown most clearly in Fig. 7. By this means the spreader bar 14 can be readily shifted and when a weight is applied to the straps, the tendency for the straps to straighten out will cause them to bind firmly against the bars 17-18 of the loops and thus be securely frictionally held in connection with the bar so that the latter cannot slip from position.

The swing 9 comprises a unitary fabric supporting frame which is indicated generally by the character F. This fabric supporting frame is formed in two portions which are the substantially U-shaped back portion 19 and the bottom portion 20. The back portion 19 includes the spaced parallel side bars 21 and a cross-connecting bar 22, while the bottom portion comprises the spaced parallel side bars 23 and a cross-connecting front bar 24. To these two portions 19 and 20 of the swing frame are secured the fabric back 25 and the fabric seat bottom 26, these being joined together to form a single unit in the customary manner.

The bottom portion of the swing frame has the rear ends of its two side bars 23 shaped to provide an obliquely directed elongated loop 27 which includes the two-spaced parallel relatively long portions 28 and the short transverse portions 29 and 30, the portion 29 constituting a hinge bar while the portion 30 constitutes a stop against which the side bar 21 of the back portion 19 bears in the manner illustrated in Figs. 3 to 5, when the swing is set up for use. The oblique elongated loop 27 extends downwardly and rearwardly from the bottom portion 20 of the frame, as is clearly shown in Fig. 1.

Each of the side bars 21 of the back portion 19 of the seat frame terminates in a hinge eye 31 through which a hinge bar 29 extends and the bar 21 bears against the rear side of the stop bar 30 and thus is locked or secured against forward swinging movement with respect to the seat portion 20, but, as will be readily seen, the back portion 19 may be swung rearwardly and downwardly and around to the under side of the seat portion when the swing is taken down, so that it may be folded.

The suspension straps 10 and 11 of Figs. 1 and 2, and 10^a, 11^a of Fig. 6, are joined respectively with the forward part of the seat portion 20 of the swing frame and with the top of the back

portion 19 thereof. As will be readily seen, with this strap arrangement, the tendency is to pull the two portions of the frame together, but due to the special hinge connection between these portions, the back will be maintained in a desired rearwardly leaning position and cannot collapse on the bottom portion even though the tendency of the suspension straps is to pull the two portions together. Thus with this arrangement the swing may be suspended either from two suspension points or from a single suspension point without requiring the use of the customary rectangular spreader frame for holding the suspension straps apart and for preventing the back of the seat frame being pulled forwardly so as to make the use of the seat uncomfortable for a child. In the two-point suspension no spreading means at all is necessary and in the single-point suspension, there is only required the single bar for holding the pairs of straps against convergence directly from their points of connection with the swing frame. This bar, however, is located upon the transverse center of the swing and, therefore, will not offer interference to the putting of a child into the swing or taking him out of the same as is the case with the use of a rectangular spreader frame where the front side of such frame is directly above the front part of the swing.

The numeral 32 generally designates a toy tray or basket which is supported upon a suitable frame having side members 33 which are slidably joined to the side portions or bars 23 of the seat frame so that the receptacle can be moved in and out, as desired.

What is claimed is:

1. A swing construction of the character described, comprising a seat and a back, a hinge coupling between the seat and back, said coupling including a back carried portion and a seat carried portion, a stop forming a part of one portion and engageable by the other portion, said portion and the stop cooperating when in one relation to maintain the back in an upwardly and rearwardly inclined position with relation to the seat, said portions and stop being arranged to facilitate swinging the back rearwardly and downwardly to a folded position beneath the seat, a pair of suspension straps at each side of the seat, one strap of each pair being connected with the front part of the seat and the other strap of each pair being connected to the back, and a suspension means connected with the pairs of straps.

2. A swing construction, comprising a frame consisting of a seat portion and a back portion, each of said portions including spaced side bars, an interlocking hinge coupling between ends of the side bars of said portions, said coupling being so constructed and arranged that the back portion is limited against forward swinging movement beyond a predetermined position in which it is maintained at an upward and rearward inclination with respect to the seat portion but is permitted rearward and downward swinging movement to a folded position beneath the seat portion, a fabric back and seat bottom secured to the frame, and suspending means connected with the frame back and seat portions.

3. A swing construction, comprising a frame consisting of a seat portion and a back portion, each of said portions including spaced parallel side bars, a hinge bar connected with each side bar of the seat portion to extend transversely thereof in offset relation with the same, a hinge

eye carried by each side bar of the back portion and having pivotal engagement with a hinge bar, means connected with and disposed adjacent to each hinge bar forming a stop for contact by the adjacent bar of the back portion, said stops limiting movement of the back portion forwardly with respect to the seat portion beyond a position in which the back portion is disposed at a rearward inclination with respect to the seat portion when the latter is horizontal, said eye and bar connection between the back and seat portions facilitating the rearward and downward swinging of the back portion to a folded position beneath the seat portion, a back and seat bottom fabric connected with the back and bottom portions of the frame, and means connected with said back and bottom portions for suspending the frame.

4. A swing construction, comprising a frame consisting of a seat portion and a back portion, each of said portions including spaced parallel side bars, a hinge bar connected with each side bar of the seat portion to extend transversely thereof in offset relation with the same, a hinge eye carried by each side bar of the back portion and having pivotal engagement with a hinge bar, means connected with and disposed adjacent to each hinge bar forming a stop for contact by the adjacent bar of the back portion, said stops limiting movement of the back portion forwardly with respect to the seat portion beyond a position in which the back portion is disposed at a rearward inclination with respect to the seat portion when the latter is horizontal, said eye and bar connection between the back and seat portions facilitating the rearward and downward swinging of the back portion to a folded position beneath the seat portion, a back and seat bottom fabric connected with the back and bottom portions of the frame, and means connected with said back and bottom portions for suspending the frame, said hinge bars and stop bars comprising portions of an elongated loop formed as an integral continuation of a side bar of the seat portion, the loops extending obliquely rearwardly and downwardly from the seat portion when the latter is horizontally disposed and the stop bars being at an elevation above the hinge bars.

5. A swing construction of the character described, comprising a seat and a back, a hinge coupling between the seat and the back comprising interconnected units, one of said units including an obliquely directed elongated loop portion and the other of said units including a hinge eye encircling a lower element of said loop portion and an elongated part movable into abutting relation with an upper element of said loop portion to maintain the back against forward movement with respect to the seat beyond a position in which it is disposed at a predetermined rearward inclination to the seat when the latter is horizontal, said back being swingable rearwardly and downwardly about said hinge coupling to a folded position upon the under side of the seat, a pair of straps at each side of the seat, one strap of each pair being connected to the forward portion of the seat and the other strap of each pair being connected to the back, the straps of each pair extending upwardly in convergent relation and being disposed in the vertical front to rear plane of the adjacent side

of the seat, the points of convergence of the straps of both pairs being substantially upon the transverse vertical center of the seat, and suspension means connected with the straps above their points of convergence.

- 5 their points of convergence.

6. A swing construction of the character de-
scribed, comprising a seat and a back, a hinge
coupling between the seat and the back comprising
interconnected units, one of said units in-
10 cluding an obliquely directed elongated loop por-
tion and the other of said units including a hinge
eye encircling a lower element of said loop por-
tion and an elongated part movable into abut-
15 ting relation with an upper element of said loop
portion to maintain the back against forward
movement with respect to the seat beyond a po-
sition in which it is disposed at a predetermined
20 rearward inclination to the seat when the latter
is horizontal, said back being swingable rear-
wardly and downwardly about said hinge cou-
pling to a folded position upon the under side
25 of the seat, a pair of straps at each side of the
seat, one strap of each pair being connected to
the forward portion of the seat and the other
30 strap of each pair being connected to the back,
the straps of each pair extending upwardly in
convergent relation and being disposed in the
35 vertical front to rear plane of the adjacent side
of the seat, the points of convergence of the
straps of both pairs being substantially upon the
transverse vertical center of the seat, a bar mem-
ber extending across between the pairs of straps
40 and joined thereto at their points of convergence,
the pairs of straps converging and being cou-
pled together above said bar upon the trans-
verse center of the bar.

7. A swing construction of the character de-
scribed, comprising a seat and a back, a hinge
coupling between the seat and the back com-
45 prising interconnected units, one of said units
including an obliquely directed elongated loop
portion and the other of said units including a
hinge eye encircling a lower element of said loop
portion and an elongated part movable into
50 abutting relation with an upper element of said
loop portion to maintain the back against for-
ward movement with respect to the seat beyond
a position in which it is disposed at a predeter-
mined rearward inclination to the seat when the
55 latter is horizontal, said back being swingable
rearwardly and downwardly about said hinge
coupling to a folded position upon the under side
of the seat, a pair of straps at each side of the
seat, one strap of each pair being connected to
60 the forward portion of the seat and the other
strap of each pair being connected to the back,
the straps of each pair extending upwardly in
convergent relation and being disposed in the
vertical front to rear plane of the adjacent side
65 of the seat, the points of convergence of the
straps of both pairs being substantially upon the
transverse vertical center of the seat, a bar mem-
ber extending across between the pairs of straps
and joined thereto at their points of convergence,
70 the pairs of straps converging and being coupled
together above said bar upon the transverse cen-
ter of the bar, said bar being formed at each
end to provide a sliding buckle loop through each
of which loops the adjacent pair of straps is
slidably extended to be held thereby in the first
stated convergent relation.

JOSEPH C. ANDERECK.
